W. CANOVA

SHUTTLE TENSION

Filed Aug. 4, 1922

WITNESS

W. M. Bell

INVENTOR,
William Canova,
BY
John Stewart,
ATTORNEY.

UNITED STATES PATENT OFFICE.

WILLIAM CANOVA, OF PATERSON, NEW JERSEY.

SHUTTLE TENSION.

Application filed August 4, 1922. Serial No. 579,592.

To all whom it may concern:

Be it known that I, WILLIAM CANOVA, a citizen of the United States, residing at Paterson, in the county of Passaic and State 5 of New Jersey, have invented certain new and useful Improvements in Shuttle Tensions, of which the following is a specification.

This invention relates to shuttle tensions, 10 for example of the class in which there is a set of guides formed by pins arranged in the shuttle body and another set guides, usually in the form of a lever pivoted in the shuttle body, movable transversely of 15 the filling into and out of alternation with the pins and normally held out of alternation therewith by elastic means so that the two sets coact normally to maintain the filling in zig-zag arrangement. The pins 20 are usually driven with a tight fit into holes bored in the shuttle body, with their ends countersunk and covered by cement. The filling in time cuts nicks in them and in order to replace them they have to be re- 25 moved by an implement with a sharp edge which is inserted into such an opening as *c* in the annexed drawing and used to nick or burr them and then pry them endwise out of their holes. This is a tedious operation 30 and it renders the pins unsuitable for further use on account of the nicking or burring, even though they might otherwise be reintroduced into their holes turned so as not to present the thread-formed nicks to 35 the filling. Moreover, usually but a single removal of the pins enlarges the holes so much that they cannot be depended upon not to work out, which of course might do serious damage to the warp. The object 40 of this invention is to provide a shuttle tension of the class indicated in which the set of guides formed by the pins will last without becoming filling-nicked much longer than such guides as heretofore devised and 45 which can be applied to any shuttle, even those already in use, without material expense or trouble.

In the drawing,

50 Fig. 1 is a plan view of a fragment of a shuttle embodying my invention;

Fig. 2 is a side elevation thereof, partly in section; and

Fig. 3 shows a plan and side elevation of a certain plate *l*.

In said drawing, *a* is a shuttle body, *b* is its cavity for the reception of the filling package, and *c* the usual opening formed in the shuttle body from one side to the other thereof, *d* being a filling-passage connecting the cavity *b* and opening *c* and *e* the channel through which the filling *A* is delivered from the shuttle. *f* is the set of guides in the form of a lever pivoted at *g*, the guides proper projecting in a row from the shank of the lever in the usual way so that they may take alternating interposed positions between the set of guides formed by the pins to be described. This lever is normally held in the position shown by a suitable elastic device *h* so that it bears against a surface *i*; it is adapted to be drawn more or less away from said surface by the filling when tensioned. What has been so far described is all well known in the art.

The set of guides formed by the pins aforementioned is indicated at *j*. This set of pins is, as usual, arranged in a row which converges toward the pivot end of the set of guides *f* when the latter is in its rest position or abutting the surface *i*; but, as is frequently the case, there may be an additional pin in the set (as *j'*) arranged out of the row to permit an extended bend to be put in the filling and thus increase the tension, if desired. For the reception of the pins there are drilled into the shuttle body from the top thereof the holes *k*, they being closed at their lower ends, as by drilling short of the under side of the shuttle body. These holes are larger in diameter than the pins, which are received therein, as shown in Fig. 1; that is, they are sufficiently larger than the pins so that always (though the wood of the shuttle should swell from moist atmospheric condition) they may be dislodged from the holes by an impact applied at the top of the shuttle body, as by holding it in one hand and striking it against the other, and normally they will rattle in the holes when the shuttle is shaken.

For maintaining the pins in the holes there is provided a plate *l* common to all of them and secured to the top face of the shuttle body by the screws *m*, but preferably in such manner that it does not interfere with the perfectly free rotation of the pins. In the preferred construction a recess *n* is formed in the shuttle body for the re-

ception of this plate so that its exposed surface will be flush with the top surface of the shuttle body.

By my construction the pins revolve with perfect freedom in response to the very delicate tractive action of the filling, so that nicks are formed therein only after very long use of the shuttle, the revolutionary shifting of the pins being enhanced by the actual lateral lost-motion which they have in the holes. When for any reason any of the pins requires to be replaced with a new one, having removed the plate *t* the operator can dislodge the pins in the way explained without any implement.

My invention can be readily and inexpensively applied to shuttles already in use, in which case it is only necessary to re-

move the pins thereof and insert a set which will be loose therein and then affix the retaining plate *t*.

Having thus fully described my invention, what I claim and desire to secure by Letters Patent is:

In combination, a shuttle body having a set of substantially parallel elongated holes entering thereinto from one surface thereof, a set of elongated cylindrical pins freely revolvable and having transverse lost-motion in the holes and forming filling guides, and means at the ends of the pins to retain them against displacement out of the holes, such means at one end of each pin being removable.

In testimony whereof I affix my signature.

WILLIAM CANOVA.
